Des. 72,552

UNITED STATES PATENT OFFICE.

DAVID O. FORD, OF LYNCHBURG, VIRGINIA.

DESIGN FOR A PAPER SALT SHAKER.

Application filed March 7, 1927. Serial No. 20,993. Term of patent 14 years.

To all whom it may concern:

Be it known that I, DAVID O. FORD, a citizen of the United States of America, residing at Lynchburg, in the county of Campbell and State of Virginia, have invented a new, original, and ornamental Design for a Paper Salt Shaker, of which the following is a specification, reference being had to the accompanying drawing, forming a part hereof.

The drawing is a perspective view of a paper salt shaker showing my design.

I claim:

The ornamental design for a paper salt shaker, as shown.

DAVID O. FORD. [L.S.]
